(57) **CLAIM**

The ornamental design for a rotary device, as shown and described.

DESCRIPTION

FIG. 1 is a top, front, left-side, perspective view of a rotary device;

FIG. 2 is a top, front, right-side, perspective view thereof;

FIG. 3 is a left-side view thereof;

FIG. 4 is a right-side view thereof;

FIG. 5 is a rear view thereof;

FIG. 6 is a front view thereof;

FIG. 7 is a top view thereof; and,

FIG. 8 is a bottom view thereof.

The broken lines in the figures are for the purposes of illustrating portions of the rotary device and form no part of the claimed design.

1 Claim, 7 Drawing Sheets
